JOURNAL STOP

Donald E. Barton, Homewood, Ill., assignor, by mesne assignments, to American Seal-Kap Corporation of Delaware, New York, N.Y., a corporation of Delaware

Filed Apr. 3, 1961, Ser. No. 100,168
8 Claims. (Cl. 308—40)

The invention relates to railway axle journal stops mounted on the side walls of a journal box at opposite sides of the journal to oppose the same and limit the movement of the journal relative to the box, journal bearing and wedge, and to avoid pounding the edges of the bearing, waste grabbing and undue play of the journal in the box, and also to help retain either waste packing or lubricator pad in proper position and to prevent damage to the dust guard.

Among the objects of the invention are to facilitate application and removal of the journal stops to and from the box without disassembly of the trucks; to hold the stops in place securely without bolting or welding or riveting or machining the box; and to reduce the likelihood of the journal axis being inclined to its bearing axis.

These objects are attained by structure illustrated in the accompanying drawings, in which:

FIGURE 1 is a longitudinal section through a box with journal, bearing, wedge and stop structure in normal functional position but also showing the position of the parts when the box is jacked up and the bearing, wedge and stop structure is removed.

FIGURE 2 is a horizontal section on line 2—2 of FIGURE 1, some parts being broken away for better illustration.

FIGURE 3 is a vertical transverse section and view on line 3—3 of FIGURE 2.

FIGURE 4 corresponds to FIGURE 3 but illustrates another form of the invention.

The journal box has the usual Association of American Railroads contours and includes a bottom wall 1 curving forwardly and upwardly to the box opening 2, side walls 3, a top wall 4, and inner and outer rear walls 5 and 6 which cooperate with the bottom and side walls to form an oil well and a dust guard pocket 7. The axle has a dust guard seat 8, a journal 9 and a collar 10. A bearing 12 is mounted on the journal and carries a wedge 14 which supports the box. The bearing sides 12a oppose the box lugs 13 which are spaced above waste retaining ribs 15 projecting inwardly from box side walls 3. A lid L is hinged to the box to swing up from the closed position shown.

All of the above described parts form familiar construction which functions in a well-known manner to support the truck and its load. The bearing is subject to uneven wear, particularly of its lower edges, due to shifting of the bearing on and from the journal during acceleration and deceleration of the truck, which permits pounding of the journal and the entrance of cotton waste between the journal and the bearing and wear on the latter.

To prevent such results and corresponding reduction in the effectiveness of the journal and journal box assembly, there is provided a stop structure comprising a block 16 of brass, iron or composition placed between each side of the journal and the adjacent box side wall 3. Each block 16 is supported by an inwardly projecting rib 15 on the box wall and has beveled corners 17, 18 engaging respectively the top of a wall rib 15 and the inturned lower face of a bearing lug 13 spaced above the rib. These beveled corners form, in effect, opposite inclined faces which take up any play between the stops and the journal box side walls by seating against the box sides when the blocks are thrust away from each other.

2

A U-shaped yoke member of spring steel has legs 22 secured to the individual stops and extending therefrom forwardly and upwardly of the box and merging with a cross piece 23 normally disposed in a horizontal plane and its axis lies in a vertical plane spaced from the stops. Elements 22 and 23 possess sufficient resiliency to thrust the inner ends of the legs apart so that they diverge from each other as they extend from the cross piece and thereby seat stops 16 in the arcuate recesses in the box side walls between the upper faces of waste ribs 15 and the lower faces of box lugs 13.

Each stop 16 is held assembled with the yoke by a vertical pin 25 inserted through a hole in the blocks and a semiround slot in leg 22. Preferably pins 25 are split steel bushings of spring steel commonly called roll pins. They frictionally engage the sides of the holes and downward movement is limited by their contact with ribs 15.

To install the stop, the journal box is jacked up and journal wedge 14 and bearing 12 removed through the front opening in the usual manner and the stop assembly is inserted through the front opening in the box, to the position shown in broken lines in FIGURE 1, then moved downwardly and further inwardly to the position shown in full lines. Also see FIGURE 3. In both these positions, movement of the stops rearwardly of the box is limited by contact of stop fingers 16a with the forward faces of box lugs 13. Yoke 22, 23 possesses resilience so that when the upper end of the yoke bears against the journal box lid, stops 16 are yieldingly thrust rearwardly of the box until fingers 16a contact lugs 13. The usual depending lug 24 on the box top wall for positioning wedge 14 also limits inner movement of yoke cross bar 23.

The journal bearing and wedge can be inserted between the bowed legs 22 of the yoke and beneath the cross bar 23 of the yoke and this permits replacement, and subsequent removals and replacements, of the journal bearing and wedge, without removing the journal stop assembly.

FIGURE 4 illustrates another form of the invention in which the box, journal, bearing and wedge are as previously described, but the stop blocks 30 are of bimetal, such as bronze and steel, and the horizontal legs 32 of the yoke are flattened and the block metals are secured to each other and to the yoke legs by rivets 34, the rivet heads being countersunk below the surfaces of the blocks.

The elements positioning the blocks and engaging the yoke may vary substantially while retaining the feature of ready application and removal of the yoke with spaced stops without modifying the box.

Other combinations of materials may be used and the details of the structure may be varied otherwise than as shown without departing from the spirit of the invention and the exclusive use of those modifications coming within the scope of the claims is contemplated.

What is claimed is:

1. In combination with a railway journal box having side walls and a top wall and horizontal support elements on its inner side walls and a wedge-retaining lug depending from the front part of its top wall and a lid closing the outer opening of the box, journal stop structure comprising blocks of bearing material seated against said elements, and a retaining yoke having elongated legs secured to said blocks and extending from said blocks toward the forward end of the box and then upwardly and positioned between the lug and the lid and holding said blocks to their seats on said elements, there being forwardly facing elements on the box and rearwardly facing opposing elements on the blocks limiting rearward movement of the blocks in the box.

2. In combination with a railway journal box having side walls and a top wall and horizontal support elements and wedge-positioning lugs on its inner side walls and a

wedge-retaining lug depending from the front part of its wedge-retaining lug depending from the front part of its top wall, journal stop structure comprising blocks of bearing material seated against said elements and including upstanding fingers engaging said side wall lugs, and a retaining yoke having elongated legs secured to said blocks and extending from said blocks toward the forward end of the box and engaging transverse parts of the box at the front end of the latter and holding the blocks to their seats on said elements and positioning the blocks lengthwise of the box.

3. A combination of railway journal box and stop structure according to claim 2 in which the stop structure may be moved upwardly and outwardly from the box, when the box is jacked up relative to an axle journal therein and the journal bearing and bearing wedge are removed.

4. A combination of railway journal box and axle stop structure according to claim 1 in which the yoke is of resilient material and is distorted, during application of the stop structure to the box, to exert lateral thrust on the blocks to seat them against the sides of the box, and to exert thrust on the blocks to seat them on the horizontal support elements.

5. In combination, a railway axle journal having a larger diameter collar at its outer end, a journal bearing thereon with sides projecting laterally from the journal, a filler wedge on the bearing, a journal box seated on the wedge and having side walls spaced from the journal and having waste-retaining elements extending along said walls and having a top wall with a wedge-retaining lug depending from said top wall, and having a journal box lid, and journal stop structure comprising a block seated on each of said elements beneath a projecting side of the bearing and extending substantially abreast of a substantial part of the middle portion of the journal and including an upstanding finger engaging a forwardly facing part of the box side wall, and a yoke of resilient material extending forwardly from the ends of said blocks past said journal collar and upwardly and transversely of the box between said wedge-retaining lug and journal box lid, the resilience of said yoke requiring the movement of the inner portions of said legs toward each other to enter said blocks between the box side walls and requiring the outward bowing of the yoke to enter said blocks between waste-retaining element and the projecting sides of the bearing.

6. A combination of railway journal box and stop struc-

ture according to claim 1 in which the yoke legs are of spring material and may be distorted downwardly to clear a wedge and a journal bearing supporting the same so they may be inserted into and withdrawn from the box between the loop legs while the journal stop structure blocks and loop are in position as described.

5 7. A combination of railway journal box and stop structure according to claim 1 in which the forwardly facing elements are parts of journal bearing retaining stops and the stop structure blocks are beneath said bearing stops and said rearwardly facing elements comprising upstanding lugs located at the ends of the stop structure nearer the front of the box.

10 8. Railway axle box stop structure comprising a U-shaped yoke having a cross piece normally disposed in a horizontal plane, and a pair of elongated legs extending transversely from the opposite ends of the cross piece downwardly below the horizontal plane thereof and then horizontally and at substantially the same level beyond a vertical plane containing the cross piece axis, the yoke being of spring material and normally positioning said legs so that they diverge from each other as they extend away from the cross piece, and being adapted to loosely straddle a railway axle journal and end collar, and a pair 15 of blocks mounted on the end portions of said legs remote from the cross piece, the yoke being distortable to 20 position the legs and blocks substantially parallel to each other.
